BOBBIN CAN FOR AUTOMATIC LOOMS

Application filed December 13, 1930. Serial No. 502,190.

This invention relates to improvements in devices for increasing the length of travel of an expelled bobbin in a weft replenishing loom and it is the general object of the invention to provide means which will cause the bobbin to traverse a greater path than is now required and to interpose in that path means for holding yarn of the weft end which extends from the expelled bobbin.

10 In weft replenishing mechanisms of the type wherein the bobbin is replaced it is customary to eject the exhausted bobbin by means of a transfer mechanism toward a so-called bobbin can standing on the floor of the 15 weave shed and located under a chute which ordinarily forms part of the lay of the loom. At the time of transfer there is extending from the near selvage of the cloth a length of weft which lies along the lay and extends 20 between the shuttle and the binder and then through the shuttle eye to the reserve bunch of weft on the bobbin. In certain classes of weaving some difficulty is experienced in withdrawing this length of weft completely 25 from the shuttle box or out of the path of the moving shuttle. Unless the thread is taken out of the shuttle box there is danger that it will be whipped into the shed to form a thick place or a so-called drawn-in end.

30 The previously mentioned cans are of sufficient depth so that when they are substantially empty the bobbin has a long enough travel from the lay to withdraw the thread, but as the can is filled the distance through 35 which the bobbin can travel is reduced with the result that the thread is not always pulled out of the shuttle box. It is an important object of my present invention to provide a bobbin can having a passage therein curved 40 so as to require the bobbin to move through a substantial path before actually entering the main part of the can. In this way a greater opportunity is given for the bobbin to extract the trailing end from the box by 45 its movement subsequent to transfer.

As shown herein the increased travel of the bobbin is provided by means of a scroll compartment having a receiving mouth located directly under the lay, the scroll being 50 so formed as to have an inside diameter of

appreciable length along which the trailing end can be wrapped as the bobbin travels to the can proper.

It is a further object of the invention to provide the receiving portion of the scroll with a surface to engage the butt of the bobbin and retard the movement of the latter so that the tip end will be in leading position as the bobbin moves through the scroll.

With these and other objects in view which will appear as the description proceeds, my invention resides in the combination and arrangement of parts hereinafter described and set forth in the claims.

In the accompanying drawing wherein I have shown one form of the device for increasing the length of movement of the expelled bobbin,

Fig. 1 is a front elevation of a well-known form of weft replenishing loom having associated therewith a can made according to my present invention.

Fig. 2 is a side elevation taken in the direction of arrow 2, Fig. 1, and

Fig. 3 is a horizontal section on line 3—3 of Fig. 1, showing the can in plan view.

Referring particularly to Figs. 1 and 2, I have shown a loomside 10 and a breast beam 11 together with a magazine designated generally at 12. A transfer mechanism 13 forming part of the magazine is adapted in well-known manner to engage a reserve bobbin 14 which may be in transfer position and insert it in the weft chamber of the shuttle 15, at the same time expelling the exhausted bobbin. The lay 16 may carry the usual bunter 17 to engage a latch 18 forming part of the transfer mechanism, the latch being controlled by means of the rod 19 which is acted upon by well-known mechanism to lift the latch into the path of the bunter when a transfer is about to take place. The lay is provided with a slot 20 through which the expelled bobbin 21 carried by the shuttle 15 may pass in its downward movement incident to transfer.

The matter thus far described is well-known in the art and of itself forms no part of my present invention.

In carrying my invention into effect I pro-

vide a bobbin can 30 which may have a body formed with upright walls 31 which define a substantially rectangular chamber shown in Fig. 3 at 32. The can has associated therewith a hollow scroll 33 having an upwardly turned mouth 34 preferably of rather narrow rectangular form but of sufficient width to receive the expelled bobbin. As shown in Fig. 1 the left hand side of the scroll immediately beneath the mouth has a downwardly inclined and curved surface 35 which cooperates with the substantially vertical right hand wall 36 to form a funnel terminating in a delivery tube 37. The latter is curved as shown in Fig. 1 to form a loop terminating in a flared or funnel shaped end 38 which opens directly into the main bobbin can 30.

In operation the mouth 34 will lie directly under the lay as suggested in Fig. 2 and the downwardly moving bobbin will have its butt end retarded by engagement with the surface 35 so that the tip end will advance, said tip end sliding along the larger internal surface 39 of the tube 33 and preferably entering the bobbin can in advance of the butt of the bobbin.

The wall 40 which defines the shorter curved part of the scroll is made of sufficient length to accommodate a relatively long length of trailing end. In order to increase the length of this interior curved surface 40 the tube 37 may be made relatively small but of sufficient size that a bobbin can move freely therethrough.

From the foregoing it will be seen that I have provided simple means for increasing the length of travel of a weft bobbin after being expelled from an exhausted shuttle and have interposed in the increased path through which the bobbin passes structure which will engage and guide the trailing end. As shown herein the increased path is accomplished by means of a scroll although I do not wish to be limited to this particular construction inasmuch as any relatively fixed guides located to increase the path of the bobbin will serve to aid the withdrawing of the weft ends.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom operating with a shuttle, means to expel an exhausted bobbin from the shuttle, a receptacle for the bobbin, and means defining a looped guide through which the bobbin passes interposed between the shuttle and receptacle.

2. In a weft replenishing loom operating with a shuttle, means to expel an exhausted bobbin from the shuttle, a receptacle for the

bobbin, and means presenting a looped surface between the shuttle and the receptacle over which the bobbin must pass before reaching the receptacle.

3. In a weft replenishing loom operating with a shuttle and having means to expel an exhausted bobbin from the shuttle, a spent bobbin receptacle having a mouth and a guide provided with a looped bobbin guiding surface and a thread engaging element within the bobbin guiding surface, said guiding surface requiring the bobbin to move around the element to wrap the trailing weft thereof around said element. 70

4. In a weft replenishing loom operating with a shuttle and having means to expel an exhausted bobbin from the shuttle, a bobbin receptacle, and a tubular guide in the form of a scroll supported by the receptacle and having a bobbin receiving mouth under the shuttle, the scroll being so located that the expelled bobbin is required to pass therethrough before entering the receptacle. 80

5. A bobbin receptacle for a loom operating with a shuttle from which an exhausted bobbin may be expelled, said receptacle having a looped tubular guide provided with a mouth adjacent the shuttle and shaped to guide a bobbin through a substantially looped path of movement before reaching the receptacle. 90

In testimony whereof I have hereunto affixed my signature.
